PTO

UNITED STATES PATENT OFFICE

147,015

DESIGN FOR A BRACELET

William Lutz, New York, N. Y.

Application June 26, 1946, Serial No. 131,037

Term of patent 3½ years

(Cl. D45—4)

To all whom it may concern:

Be it known that I, William Lutz, a citizen of the United States of America, residing in New York, county of New York, and State of New York, have invented a new, original, and ornamental Design for a Bracelet, of which the following is a specification, reference being had to the accompanying drawing, forming part thereof.

Fig. 1 is a front perspective view of a bracelet showing my new design.

Fig. 2 is a plan view in open position.

Fig. 3 is an edge view of Fig. 2.

I claim:

The ornamental design for a bracelet, substantially as shown.

WILLIAM LUTZ.
